UNITED STATES PATENT OFFICE

102,000

DESIGN FOR AN INSTRUMENT CASE

Harry Y. Norwood, West Rush, and Harold S. Robbins, Rochester, N. Y., assignors to Taylor Instrument Companies, Rochester, N. Y., a corporation of New York

Application October 6, 1936, Serial No. 65,184

Term of patent 14 years

To all whom it may concern:

Be it known that we, Harry Y. Norwood and Harold S. Robbins, citizens of the United States of America, residing respectively at West Rush and Rochester, county of Monroe, State of New York, have invented a new, original, and ornamental Design for an Instrument Case, of which the following is a specification, reference being had to the accompanying drawing, forming a part thereof, wherein:

Fig. 1 is a front view of an instrument case showing our new design; and

Fig. 2 is a side view thereof.

We claim:

The ornamental design for an instrument case, as shown.

HARRY Y. NORWOOD.
HAROLD S. ROBBINS.
